DES. 1967

John Rogers, of New York, N.Y.

Letters Patent No. 1967-Dated June 28th 1867.

Design for a Group of Figures

The schedule referred to in these Letters Patent and making part of the same.

To all whom it may concern:

Be it known that I, John Rogers, of the City and County of New York, have invented or produced a new and original design for a statuette group of figures and I do hereby declare that the following is a full and exact description of the same. The group consists of two figures and is called the Wounded Scout, or a friend in the swamp. It represents a ragged negro supporting on his right a soldier who has been shot through the right arm on which is a tomahawk. A copper head snake is in the swamp grass near the negro's feet. All of which are clearly seen in the accompanying drawings and what I claim as my production or invention, and desire to secure by Letters Patent is The design for a group of figures as shown and described.
